UNITED STATES PATENT OFFICE.

WILLIAM F. RANDALL, OF PHILADELPHIA, PENNSYLVANIA, ASSIGNOR TO WILLIAM T. PLUMMER, OF PHILADELPHIA, PENNSYLVANIA.

SHOE.

1,112,834.

Specification of Letters Patent.

Patented Oct. 6, 1914.

Application filed May 11, 1914. Serial No. 837,702.

To all whom it may concern:

Be it known that I, WILLIAM F. RANDALL, a citizen of the United States, residing at Philadelphia, county of Philadelphia, and State of Pennsylvania, have invented a new and useful Improvement in Shoes, of which the following is a full, clear, and exact description, reference being had to the accompanying drawings, which form a part of this specification.

The object of my invention is to provide a shoe having a sole adapted primarily to withstand extremes of heat and also to effectually exclude moisture and resist the abrasive and cutting action of sharp stones.

In certain industries the conditions are such as to be destructive of the footwear of the workmen. This is especially true of employees of steel mills and other industrial plants in which conditions of elevated temperature prevail. The workmen are often compelled to walk over heated surfaces and sometimes over red hot cinders and other highly heated substances; and then, again, they are compelled to walk over moist ground or through shallow puddles of water and over jagged solid materials. The subjection of the ordinary leather sole, no matter how thick, to these conditions, soon proves ruinous to the shoe. Indeed, standing or walking on heated surfaces is alone effectual to cause speedy disintegration of the leather of the sole and besides offers no adequate protection to the feet, causing great discomfort to the wearer. Consequently, those working under the conditions mentioned frequently find it necessary to improvise some protection for the ordinary leather-sole shoes, which consists in tying some protective material to the sole of the shoe. Such expedients involve loss of time in applying and removal and seriously interfere with comfortable walking and at best are mere makeshifts.

The object of my invention is to provide a shoe having a sole which, when the shoe is worn under the conditions specified, besides being relatively indestructible, is comfortable and sightly, and may be worn, not only during working hours, but at any other time.

A preferred embodiment of the invention is shown in the drawings in which—

Figure 1 is a side elevation of the shoe

and Figs. 2 and 3 sections respectively on 55 the lines 2—2 and 3—3 of Fig. 1.

The shoe comprises the usual vamp or upper *a*, the top *b* and the sole. The sole consists of the parts *c*, *d*, *e*, *f* and *g*. The part *c*, which extends from the front to the back of the shoe, comprises a number of sheets or layers of duck or canvas, which are stitched together and saturated with oil. Linseed oil is available for the purpose, although other oils are also found serviceable. 65 The part *d* is applied under the rear of the part *c* and forms, in connection with the rear of part *c*, the heel. Like the part *c*, the part *d* comprises a number of sheets or layers of duck or canvas stitched together 70 and saturated in oil.

Preferably the parts *c* and *d* are attached to the vamp *a* in the following manner: The lower edge of the vamp, in the part thereof extending from the front of the heel 75 to the tip of the toe is brought under the edge of a leather insole *e*, which extends throughout the length of the shoe, and over the inner edge of a leather welt *f*, which extends around the margin of the shoe from 80 opposite sides of the front of the heel. This confined edge of the vamp is nailed, stapled or otherwise secured to and between the insole *e* and welt *f*. The welt *f* is secured to the sole *c*, preferably by stitches *h* extending 85 entirely through both members. Between the heel *d* and sole *c* is inserted a leather welt or skiver *g*. The heel portion of the vamp *a* has its outer edge inserted between the insole *e* and the sole *c* and is 90 secured to both members preferably by means of nails *j* extending through the welt *g* as well as through the vamp *a*, insole *e* and sole *c*. The heel member *d* is secured to the sole *c* preferably by means of nails *i* 95 extending through both parts and the intermediate welt *g*.

The leather portions of the sole, particularly the welts *f* and *g*, impart the required degree of elasticity to the shoe. The main 100 sole *c* is found to effectually resist all the deleterious conditions hereinbefore mentioned. A shoe provided with such a sole may be placed on a bed of red hot coals and may remain there until the coals cool and 105 the shoe is found to be substantially uninjured; whereas an ordinary shoe, subjected to these conditions, is to all intents and pur-

poses destroyed, the leather of the sole crumbling and disintegrating under the high temperature conditions. A shoe embodying my invention is also admirably adapted for hot climates, particularly for travel over hot desert sands or in regions where both extreme heat and great moisture coexist or alternate.

While the specific way herein set forth 10 of constructing my improved shoe has certain advantages, the invention, in its broader aspect, is not limited thereto.

Having now fully described my invention, what I claim and desire to protect by Letters Patent is:

1. A shoe comprising a vamp and an outsole composed of a number of sheets of canvas impregnated with oil and stitched together and secured to the vamp.
2. A shoe comprising a vamp, a sole member composed of a number of sheets of canvas impregnated with oil and stitched together and secured to the vamp, and a heel member also composed of a number of sheets of canvas 25 impregnated with oil and stitched together and secured to said sole member.
3. A shoe comprising a vamp, an outsole member composed of a number of sheets of canvas stitched together and impregnated 30 with oil, and a welt between the vamp and outsole member and secured to both.
4. A shoe comprising a vamp, an outsole member composed of a number of sheets of canvas stitched together and impregnated 35 with oil, and a welt between, and extending along the margin of, the vamp and outsole member from opposite sides of the front of the heel to the toe, and means securing the welt to both the vamp and outsole member.
5. A shoe comprising a vamp, a sole member composed of a number of sheets of canvas stitched together and impregnated with oil, a welt between the vamp and said sole member and secured to both, and a heel member also composed of a number of sheets 45 of canvas stitched together and impregnated with oil and secured to said sole member.
6. A shoe comprising a vamp, a sole member composed of a number of sheets of canvas 50 stitched together and impregnated with oil, a heel member also composed of a number of sheets of canvas stitched together and impregnated with oil, and a welt between and secured to both said members.
7. A shoe comprising a vamp, a sole member composed of a number of sheets of canvas stitched together and impregnated 55 with oil, a welt between the vamp and said sole member and secured to both, a heel member also composed of a number of sheets 60 of canvas stitched together and impregnated with oil, a welt between the heel member and the sole member, and securing means

engaging said sole member, the last named welt and the heel member.

65

8. A shoe comprising a vamp, a sole member composed of a number of sheets of canvas stitched together and impregnated with oil, a welt extending between, and along the margin of, the vamp and outsole member 70 from opposite sides of the front of the heel to the toe, and secured both to the vamp and said sole member, and a heel member also composed of a number of sheets of canvas stitched together and impregnated with oil 75 and secured to said sole member.

9. A shoe comprising a vamp, a sole member composed of a number of sheets of canvas stitched together and impregnated with oil, a welt extending between and along the 80 margin of, the vamp and outsole member from opposite sides of the front of the heel to the toe and secured both to the vamp and said sole member, a heel member also composed of a number of sheets of canvas 85 stitched together and impregnated with oil, and a welt between and secured to both said sole member and heel member.

10. A shoe comprising an outsole composed of a number of sheets of canvas 90 stitched together and impregnated with oil, an insole, a vamp, and a welt, said welt extending between the lower margin of the vamp and the outsole and secured to both, and the vamp extending between said welt 95 and insole and secured to both.

11. A shoe comprising an outsole composed of a number of sheets of canvas stitched together and impregnated with oil, an insole, a vamp, and a welt, said welt extending between the lower margin of the 100 vamp and the outsole and secured to both, and the vamp extending between said welt and insole and secured to both, and a heel member also composed of a number of sheets 105 of canvas stitched together and impregnated with oil and secured to said outsole.

12. A shoe comprising an outsole composed of a number of sheets of canvas stitched together and impregnated with oil, 110 an insole, a vamp, and a welt, said welt extending between the lower margin of the vamp and the outsole and secured to both, and the vamp extending between said welt and insole and secured to both, a heel member also composed of a number of sheets of canvas 115 stitched together and impregnated with oil, and a welt extending between and secured to both said members.

In testimony of which invention, I have 120 hereunto set my hand, at Philadelphia, on this 8th day of May, 1914.

WILLIAM F. RANDALL.
